CLAIM

The ornamental design for an electroluminescent night light, as shown.

DESCRIPTION

FIG. 1 is a perspective view of an electroluminescent night light showing my new design;

FIG. 2 is a front elevational view of the electroluminescent night light of FIG. 1;

FIG. 3 is a side elevational view of the electroluminescent night light of FIG. 1; and,

FIG. 4 is a top plan view of the electroluminescent night light of FIG. 1.

The rear of the electroluminescent night light housing is flat and plain except for the electrical connector prongs. The prongs extend from the enlarged lower portion of the housing under the recess. The prongs extend a greater distance from the housing than the thickness of the housing.
